UNITED STATES PATENT OFFICE

JAMES CLYDE RAINY, OF GROVE CITY, PENNSYLVANIA

DESIGN FOR A TRAFFIC-SIGNAL CASING

Application filed November 18, 1929. Serial No. 33,482. Term of patent 7 years.

To all whom it may concern:

Be it known that I, JAMES CLYDE RAINY, a citizen of the United States of America, residing at Grove City, in the county of Mercer and State of Pennsylvania, have invented a new, original, and ornamental Design for a Traffic-Signal Casing, of which the following is a specification, reference being had to the accompanying drawing, forming a part hereof.

In the drawing:

Figure 1 is an elevation of a traffic signal casing showing my design, and
Fig. 2 is a plan view of the same.

I claim:

The ornamental design for a traffic signal casing, as shown.

JAMES CLYDE RAINY. [L.S.]
